Attorney

UNITED STATES PATENT OFFICE

HERMANN KRAUTER, OF VIENNA, AUSTRIA
MASSAGING AND STIMULATING IMPLEMENT

Application filed August 3, 1931, Serial No. 554,835, and in Germany August 4, 1930.

The present invention relates to an apparatus for the treatment of the skin, more particularly of the face, by what may be termed a massage or similar treatment effected by pressure, friction and suction. Apparatus of this kind are already known, but they are made in such a way that, owing to the difficulty of manipulating them properly, they do not exercise the desired effect, or at least not to its fullest extent. One example is the case of an apparatus in which the members used for the purpose of carrying out the treatment are mounted in such a manner on a three-armed carrier or mount, having on one arm a suction bottle, on the second arm a pressure or friction head, and on the third arm an india rubber ball by means of which the suction effect is produced in the suction bottle and which at the same time is used for guiding the apparatus or as a handle therefor. The consequence of using the rubber ball as a handle or as a guide is that the members used for the purpose of carrying out the massage or similar treatment do not, when pressure or friction or suction is being applied, come into contact with the skin in such a way as to allow these members to function properly, because the rubber ball is soft and flexible and, more particularly when it is collapsed, does not offer the resistance necessary to ensure proper guiding during the application of the massaging members.

The subject matter of the invention, however, comprises an apparatus for the treatment of the skin and in which the pressure or friction member, for example, a glass bulb which is capable of being filled with a liquid, and the suction member, for example a suction bottle, are so arranged on a handle that they can be used immediately one after the other in sequence, the suction effect being produced in the suction member with the aid of a suction device arranged on the handle and consisting for example, of an india rubber ball, which functions for that purpose only. The handle consists of a rod, adapted preferably to fit the palm of the hand when closed, and made of any desired material, and which, at one end, may

be formed in the shape of a sleeve, carries the pressure or friction member. In the exemplary form this pressure or friction member is a glass bulb and has a screw union with the handle end, and is capable of being 55 so screwed into the end that, according to the position of the bulb, it can be filled with water entering through a plurality of openings arranged in the adjacent end of the handle. The bulb when filled is screwed completely into the end of the rod, and a seal is made in such a way that the water contained in the bulb cannot escape. In order to facilitate the admittance of the liquid into the bulb when the openings are exposed and to displace any air that may be present, a pin as hereinafter referred to projects into the neck of the bulb. This pin is carried by the end of the handle.

The other end of the handle is tubular, or carries a tubular attachment, which is provided in such a manner with a suction member or bottle and a suction device such as a collapsible ball that the working chamber of the suction device communicates by way of the openings arranged in the tubular portion with the suction bottle.

The handle is rigidly connected to the two members which act on the skin as also to the suction device. With such an arrangement the desired pressure or the necessary friction can be applied by the massage bulb and regulated as desired, and the suction member or bottle can also be applied in such a way that it lies closely against the skin and exercises a good suction effect. The suction device can at the same time be actuated without unfavorably influencing the manipulation of the parts used for treating the skin.

One form of construction of apparatus for the treatment of the skin according to the present invention is shown by way of example in the appended drawing. Fig. 1 is a longitudinal section through the apparatus and Fig. 2 a section through the sleeve-like end of the handle fitted with the massage bulb, this being in the position permitting the admittance of water.

Referring to the drawing, at one end of a rod shaped handle *a* which is adapted to fit 100

the closed palm of the hand, is arranged a
5 massage bulb *b*, and at the other end a suc-
tion cup or bottle *c*. The massage bulb *b* is
of known form and consists of a hollow glass
body having a flat-arched working surface.
The bulb *b* is provided with a connecting neck
10 *d* having an external screw thread *e* which
engages an internal screw thread on the
sleeve-like end *f* of the rod *a*. This end *f* is
provided with a number of holes *g* through
15 which, when the bulb *b* is in the position
shown in Fig. 2, water can flow into the
bulb, whereas, when the bulb *b* is in the posi-
tion shown in Fig. 1, these holes are shut off
20 and the water trapped in the bulb *b*. Within
the neck *d* of the bulb is located a pin *h* having
a foot disc *i*. The pin is held to the sleeve *f*
by means of a rubber cover plate or disc *k* pro-
25 vided at the bottom of the recess in the sleeve.
This cover plate or disc forms a packing for
the bulb neck when the bulb is in the position
shown in Fig. 1.

At the other end of the handle *a* is a longi-
tudinally bored stem or tubular extension
25 member *l*, which is screwed into the handle.
This member *l* has lateral openings *m*. The
end of the member *l* remote from the handle
has a screw thread *n*, engaging one end of
30 a sleeve *o* which has a central bore or channel
passage-way *p*. This sleeve *o* has an internal
thread *q* engaging an external thread on the
neck *r* of the suction bottle *c*. The suction
bottle *c* and the neck *r* have a bore or passage-
way *s*.

35 Drawn over the member *l* and a part of the
sleeve *o* is a ball *t* which at the holes *u* and *v*
is made watertight on the one hand relatively
to the tubular extension and on the other
hand relatively to the sleeve *o*. For packing
40 or other purposes, the handle *a* can be taken
apart, a screw union *w* being provided.

The manipulation and the method of using
the apparatus are as follows:—

45 The end of the apparatus carrying the fric-
tion or pressure bulb *b*, after the bulb is par-
tially unscrewed as shown in Fig. 2, is dipped
obliquely into warm water, in such a way that
some of the holes *g* are in the water and allow
the water to enter, the air being allowed to
50 escape through those holes *g* not immersed.
The pin *h* will form what may be termed a
guide or partition wall for the water and the
air, so as to allow a rapid influx of water to
and a rapid outflow of air from the bulb *b*.
55 As soon as the bulb *b* is full of hot water, it
is screwed into the sleeve *f* until the lower end
of its neck *d* presses against the rubber disc or
washer *k*, thus shutting off the holes *g* and
60 also preventing escape of the water. When
the bulb is being screwed in, the above men-
tioned pin *h* will displace the water in the
bulb and the water will thus rise to such a
height in the bulb that it will displace all the
65 air out of the bulb. The bulb is then pressed

or rubbed against the skin which can either be
bare or previously moistened and dressed
with cream, so that by the combination of
friction or pressure and the heat of the bulb
the pores of the skin will be opened. When
70 the skin is in this condition, the suction device
is brought into play, in order to remove im-
purities from the opened pores. To do this,
the apparatus must be turned round the oper-
ator holding the handle by the rigid common
75 handle *a*, the rubber ball being at the same
time collapsed, and the suction bottle *c* laid
against the skin. After the rubber ball has
been released by the fingers, the suction bottle
80 *c* is drawn along the surface of the skin and
the impurities are drawn out of the pores into
the suction bottle. The suction bottle can
always be applied in such a manner to the
skin and drawn along it that it adheres for a
85 comparatively long time to the skin, thus al-
lowing the rubber ball *t* to exercise a pro-
longed suction effect.

With apparatus according to the present
invention a rapid interchange of the friction
or pressure member, which imparts a pre-
liminary heat to the skin, and the suction
member is possible, as also the application of
the suction member to the skin in such a way
90 that it lies closely against the skin and conse-
quently exercises a suction effect for a com-
paratively longer period. With the improved
apparatus the skin receives a much better
treatment than by the known devices men-
tioned.

Having now particularly described and as-
certained the nature of my said invention and
in what manner the same is to be performed,
I declare that what I claim is:—

1. A massaging and stimulating device
comprising a handle to be grasped by the
hand of the user and adapted to support a
massage bulb at one end thereof, a longitudi-
nally bored stem extending from the opposite
105 end of the handle, said stem having lateral
openings, a flexible bulb supported on and
surrounding the stem and the openings, and
means rigidly secured to the stem adapted for
attaching a suction cup thereto, said means
110 having an aperture extending therethrough
for communicating with said stem and cup.

2. A massaging and stimulating device
comprising a handle to be grasped by the
hand of the user, said handle being provided
with a laterally apertured sleeve at one end
thereof, the latter having a pin positioned
115 therewithin opposite the apertures in said
sleeve, and a massage bulb movably engaging
the sleeve to uncover said apertures and to
receive said pin.

3. A massaging and stimulating device
comprising a handle to be grasped by the
user having a longitudinally bored stem ex-
tending from one end thereof and provided
with lateral openings, a flexible bulb sup-
120 ported on and surrounding the stem and the
125

openings, a bored sleeve secured to the stem and a cup having a passage engaging the sleeve, the bores of the stem and sleeve and the passage of the cup being in communication.

5 In testimony whereof I affix my signature.

HERMANN KRAUTER.
